TYPEWRITING MACHINE

Filed May 2, 1930

UNITED STATES PATENT OFFICE

WILLIAM F. HELMOND, OF WEST HARTFORD, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed May 2, 1930. Serial No. 449,177.

This invention relates to the tabulating mechanisms for the carriages of Underwood and other typewriting machines, and the means for controlling the speed of the released carriage.

Certain of the improvements are suitable for typewriter-carriages of standard length, having about eight inches travel, but one of the objects of the invention is to improve 10 the tabulating mechanism of a long carriage and also to improve the action of the carriage when released. Sometimes a long carriage travels twenty-four inches or more, and occasionally the carriage may jump fifteen 15 or twenty inches, and it is desired to prevent the carriage from gaining undue momentum in a long jump. The long carriages are heavy, and injury would occur to the machine by suddenly arresting the heavy carriage if 20 running at high speed. On the other hand, it is desired not to devote too much time to the carriage-jumping operation.

In the Underwood typewriters that are used for typing ordinary correspondence, in 25 which there is not much occasion for tabulating, it is contrived that the key which releases the carriage at the tabulating operation shall also press a stationary bar against a brake-pad that is fixed on the carriage, so 30 that the jumping carriage is subjected to some restraint. The carriage, however, is not fully under control, although little or no injury results from sudden arrest of the carriage, since the carriage is light and since the 35 tabulating mechanism is used infrequently. The friction pad is subject to wear.

In some machines there is provided an extra rack upon the carriage, which meshes with a pinion, and thereby rotates a friction 40 disk, which serves as a check against excessive carriage speed. This does not instantly check the carriage, and, moreover, the friction is usually inefficient where the carriage has a long range and is traveling at 45 increasing speed.

Machines have also been made with centrifugal governors, where the pressure of the carriage-brake is increased by the increasing speed of the carriage, but these may allow the 50 carriage to make a considerable jump without

checking it at all; and if the speed of the carriage should rise very much, the centrifugal governor would supply too great a braking power. Any kind of a revolving brake has to be set for a certain carriage speed, but 55 at other speeds the brake is apt to develop faults.

All of the centrifugal devices are expensive and add to the weight of the carriage and 60 moving parts.

An object of the present invention is to provide a simple and inexpensive carriage-retarding device, which is also reliable, and is efficient for both long and short jumps of the carriage, and prevents shocks from sudden 65 arrest of the rapidly moving long heavy carriage, and does not require to be set for any speed, and is economical of time of the tabulating operation, and places the action of the carriage entirely under the control of the 70 operator.

In the preferred manner of carrying out the invention, a brake-strap is extended from one end of the carriage to the other. Upon the machine-frame there is provided a pair of 75 jaws, faced with leather or suitable padded friction material; these jaws being adapted to bite upon said strap. One of the jaws is movable, and is connected to the tabulator-key that releases the carriage from the control of the escapement-mechanism; the other 80 jaw does not need to move.

When a tabular-key is depressed, one jaw presses the brake-band against the other jaw, and as the band travels, there is a double friction incurred, one upon each surface of the band, so that the efficiency of the brake is 85 double, and it is easily controlled by the key.

There may be sufficient flexibility of the band to insure the desired coaction between 90 the same and the friction jaws, since even if the band is slack, the movable jaw brings it firmly against the fixed jaw. Moreover, it is no longer necessary to provide an accurately formed and mounted brake-bar having 95 coaction with a single brake shoe, as heretofore. The device works perfectly regardless of inaccuracies of manufacture, and is not affected by wear, nor by inaccuracies which may occur in the travel of a long carriage. 100

The active jaw is provided with an arm which carries a stationary counter-stop, which is projected into the path of the column-stops mounted upon the typewriter-carriage.

The rocking jaw also has an arm which operates the carriage-release mechanism, and the parts are so set that the carriage is released at the moment that both shoes grip the brake-band; but the carriage-releasing mechanism is capable of being still further rocked, to permit the movable brake to force the band harder against the stationary brake, so as to retard the carriage more effectively.

The device is sufficiently under the control of the operator to permit him to release the carriage and let it jump freely for nearly all of a long stroke, and the pressure upon the tabulator-key may be increased sharply near the end of the carriage-stroke, thereby gradually checking the carriage and preventing shock when arrested by the column-stops. This is a time-saving device, since the operator does not have to wait while the carriage takes a long time in making long jumps slowly.

The carriage is suitably checked by the operator, and not too sharply arrested, and has little or no tendency to rebound, thus overcoming a drawback in tabulating typewriters.

A further improvement relates to the manner of mounting and operating the column-stops on the carriage, and one of its main objects is to compact the column-stop mechanism, to lighten it, and reduce its cost and make it more reliable. To the end portions of a carriage are attached rearwardly-extending brackets, which carry a column-stop bar having teeth on opposite sides, the column-stops having forks inserted between the teeth of the bar. The above-mentioned brake-band is placed near the top of the carriage, extending along its rear. Above the bar is mounted a column-stop locating scale, and this scale can be swung upwardly and forwardly to a position for convenient reading. While it is swung up, the column-stops are arranged along the bar as desired, to make use of the scale when locating the stops. Then the scale is pressed down, and a flange that is provided upon the scale locks the column-stops upon the bar.

The aforesaid arm which carries the carriage-braking jaw is hinged upon the fixed framework of the typewriting machine, preferably upon the standards which carry the rear carriage-guide rod. Said jaw extends upwardly and rearwardly from its hinge, a column-stop being secured to the upper end of the arm just behind and below the column-stop rack, the whole making a very compact structure just at the rear of the paper-carriage. The main stop extends radially of its pivot, and therefore occupies an ob-

lique position when viewed in side elevation. The column-stop bar is given a corresponding obliquity for compactness, efficiency, lightness and inexpensiveness. Moreover the brake does not press against the carriage itself, and thus there is obviated the tendency of the usual brake to cause the carriage to bind and wear upon its tracks.

Other features and advantages will hereinafter appear.

In the accompanying drawing,

Figure 1 is a fragmentary perspective view of an Underwood typewriting machine having my invention applied thereto.

Figure 2 is a partial cross-sectional view, from front to rear, of the structure shown in Figure 1, the braking mechanism being shown in released position.

Figure 3 is a view similar to Figure 2, the braking mechanism being shown in effective position.

Figure 4 is a diagrammatic view, illustrating the operating principle of my improved braking mechanism.

Figure 5 is a detail view, illustrating the construction of one of the brake-jaw members of my invention.

In the typewriting machine, types strike against a platen 11 on a platen-shaft 12, mounted in a carriage 13, traveling on a front rail (not shown) and a rear rail 14, mounted upon a main frame 15.

As a type 10 is swung by a key against the platen 11, the carriage 13 is letter-spaced to the left by a spring-motor 16 and band 17. A rack 18, displaceably mounted on the carriage 13, normally engages a pinion 20, fastened to a ratchet-wheel 21, whose step-by-step rotation is controlled by dogs 22, mounted on the main frame 15 for operation by a universal bar (not shown). The above-named parts are found in the Underwood long-carriage typewriting machine.

A flexible carriage-braking strap 23 is mounted upon the carriage by means of a rearwardly-extending bracket 24, secured by screws 25 upon a crosswise frame-member 26 at the rear side of the carriage. A rearwardly-extending bracket 27 may be mounted by screws 25 on the frame-member 26, adjacent the other end of the carriage 13.

The wear-resisting brake-strap 23 may be made of suitable flexible metal, and may have each end fastened, as by screws 28, to fastening members 30. One member 30 is secured strongly by screws 31 to the bracket 24, and the other to the bracket 27 in a like manner by screws 31.

For compactly mounting the various elements of the mechanism, the brake-strap-fas-tening members are preferably shaped sub-stantially as shown in Figures 1 and 2, and normally hold the brake-strap 23 in an oblique plane.

A bifurcated brake-jaw, generally desig-

nated as 32, is mounted in the rear of strap 23, and a fixed brake-jaw, generally designated as 33, in front of the strap. A rock-shaft 34 is mounted on pintles 35 of studs 36, threaded 5 in usual corner-post extensions 37 of the main frame 15. The brake-jaw 32 has two branches 38 coaxially apertured for engaging with a tight fit on the shaft 34, adjacent the ratchet-wheel 21, a short distance to the rear of the latter. A set-screw 40 engages through each 10 branch 38 and secures the brake-jaw member 32 on the shaft 34, to provide angular movement of the member and the shaft together. A brake-shoe element 41, of cork or other suitable 15 material, may be securely fastened to the brake-jaw member 32, so as to be disposed opposite from and nearly parallel to the strap 23, in the rear thereof.

The brake-jaw member 33 may be formed 20 from sheet-metal, and have two branches 42, each curled around the shaft 34, to permit the member 33 to turn about the shaft. The outside width of the branches 42 is such that they will fit snugly between the branches 38, 25 and are thereby held against lateral displacement. A brake-shoe element 43, of a material like the shoe-element 41, may be fastened, as by rivets 44, to the jaw-member 33, so that its work-face will be disposed parallel to 30 and closely adjacent the strap 23.

A torsion spring 45 is coiled about the shaft 34 between the branches 38, and one end of the spring presses against the member 32, and the other end presses against the member 33. To 35 hold the brake-jaw member 33 against angular movement, it has an integral forwardly-extending stop-lug 46 with a down-turned portion 47 arranged for engaging against a usual ball-bearing casing 48, which forms an element of the escapement-mechanism, and is supported by the frame 15.

When it is desired to have the carriage 13 move leftwardly a predetermined distance, more than a single letter-space, the operator 45 depresses tabulator-key 50, mounted on a key-lever 51, which is fulcrumed about a usual rod 52, the depression of the key-lever being yieldingly resisted by a spring 53. The key-lever 51 is connected by an upwardly-extending 50 link 54 to a forwardly-extending arm 55, fastened in the shaft 34. The link 54 has a slot 56 engaging about a pin 57 in the lever 51, and the link is loosely fastened to the arm 55 by a screw 58.

55 A tappet 60, fastened in the shaft 34, extends forwardly and terminates in a ball-element 61. The ball 61 is disposed adjacent an upper face of the rear end of a lever 62, which extends forwardly under the rack 18, and is 60 pivoted between the ball 61 and the rack on a rightwardly-extending stud 63, fastened in a usual upright column-element 64 of the main frame 15, provided for mounting the escapement-mechanism.

65 A roller 65 is mounted on the end of the

lever 62 in a substantially vertical plane, and is normally disposed a short distance below a shoulder-element 66 at the base of teeth 67 on the rack 18. The work-face of the brake 41, in starting position, is spaced from the work-face of the brake-shoe 43 a distance having a predetermined relation to the distance of the uppermost part of the roller 65 from the shoulder 66, so that upon initial depression of the key 50, the brake-shoe 41 moves the brake-strap 23 up against the brake-shoe 43 just before the roller 65 is swung up far enough to raise the rack 18 out of engagement with the pinion 20.

Upon disengagement of the rack 18 and the pinion 20, the spring-motor 16 moves the carriage 13 to the left at a speed which varies according to the pressure of the brake-shoes 41 and 43 on the strap 23, which moves between the brake-shoes, being connected to the carriage. The pressure of the brake-shoes 41 and 43 on this strap can be controlled by the pressure of the operator's finger on the key 50.

To bring the carriage 13 to a stop after it has been released from control of the letter-space mechanism, an upreaching stop-tooth 70 is integrally joined to a base-member 71, mounted on a rear extension 73 of the brake-jaw 32, as by rivets 72. Also the base-member may have a key-element 74 for engaging in a suitable slot in the brake-jaw extension 73.

A rack 75, of rectangular cross-section, has teeth 76 of a well-known form cut in two opposite faces, the teeth being one letter-space distance apart. The rack may be mounted on a carriage by means hereinafter described in an oblique plane substantially parallel to the plane of the brake-strap 23. Bifurcated column-stops 77 of a usual design are mounted on the rack 75 at desired points, such as those corresponding to columnar divisions of a work-sheet (not shown). The rack 75 is positioned so that when the brake-jaw member 32 is swung up to effective braking position, the tooth 70 is moved into the path of the column-stops 77 on the rack 75, and the nearest stop to the right of the tooth 70 is moved squarely up against it and brings the carriage to a stop. Upon release of the key 50, the rack 18 engages the pinion 20 just before the tooth 70 is lowered out of the path of the engaging column-stops 77.

For mounting the rack 75, the brackets 24 and 27 each has an upward and a rearward extension 80, on which the rack 75 may be fastened by screws 81. The rack may be provided with a shoulder-element 82 at each end for abutting against the extensions 80 to help to transmit the carriage-stopping impact strain coming on the rack 75 to the left extension 80.

A feature of the present invention resides in the provision of an improved tabular scale.

for setting the column-stops 77, which may include a strip 84, having usual graduations 85 and a cross-piece 86, on which the scale bearing strip 84 may be mounted by screws 87. The cross-piece 86 is mounted for upward displacement on two pivoted hinge-members 88, one at each end of the cross-piece 86. Each hinge-member has a rearward shelf-extension 89, on which the cross-piece 86 rests, and an integral forwardly-extending flange-element 90, which is apertured for receiving a pivot-screw 91, which is threaded in an upwardly-extending arm 92 of a bracket 93, mounted on top of the end portion of the rack 75 by the screws 81.

The cross-piece 86 serves an additional purpose by having a down-turned flange-member 94, whose lower edge normally engages behind a usual shoulder 95 of the column-stops 77. The cross-piece thereby serves as a lock-device for holding the column-stops securely in position. A leaf-spring detent-member 96 may be mounted on the left-hand bracket 93 by one of the screws 81. When it is desired to reset the column-stops 77, the detent-spring holding screw 81 may be slightly loosened, the spring swung aside, and the cross-piece swung up to the position indicated in dot-and-dash outline in Figure 2. The column-stops 77 may then be changed, and the cross-piece swung down again and secured in place by the detent-member.

Variations may be resorted to within the scope of the invention, and portions of the improvements may be used without others.

Having thus described my invention, I claim:

1. In a typewriting machine, the combination with a laterally movable carriage, means for urging said carriage in the direction of its letter-space travel, and mechanism for letter-spacing said carriage, of key-controlled means for releasing said carriage from said letter-spacing mechanism, whereby it is free to be moved rapidly by said urging means, instrumentalities for applying a manually variable braking force to the released carriage to retard the lateral movement thereof, said instrumentalities including a laterally disposed brake-strap on said carriage and two laterally fixed brake-jaw members mounted on said machine on opposite sides of said strap, one of said jaw-members movable for pressing said brake-strap against the other jaw-member as it moves with said carriage between them, and devices for stopping said carriage, said stopping devices including laterally adjustable column-stops on said carriage, and a stop-tooth on said movable brake-jaw member movable into the path of said column-stops upon the operation of said braking-force instrumentalities.

2. In a typewriting machine, the combination with a stationary main frame, a leftwardly-urged carriage and a letter-spacing

mechanism controlling the leftward movement of said carriage, of instrumentalities for releasing said carriage from control of said letter-spacing mechanism, including a laterally disposed rock-shaft on said main frame, a key operatively connected to said shaft for rotatively moving the same, and a connection between said shaft and said mechanism, a laterally disposed strap on said carriage substantially parallel to said rock-shaft, two laterally-fixed brake-jaws on said rock-shaft arranged for pressing said brake-strap between them upon rotation of said shaft by said key, a settable carriage-stop on said carriage, and a member on one of said brake-jaws arranged for engaging said carriage-stop and arresting the leftward movement of said carriage, said stop-member being moved to effective position upon rotation of said rock-shaft.

3. The combination with a spring-propelled letter-feeding carriage, of a tabulating mechanism including a key-operated rock-shaft, carriage-releasing means operated by said rock-shaft, a friction strap anchored at its ends to the rear portion of the carriage, a stationary friction jaw for cooperation with said strap, and an arm extending upwardly from said rock-shaft and having a friction surface for pressing said strap against said stationary friction jaw when the carriage is released, said arm having an upward extension provided with a counter-stop for engagement with a column-stop upon the upper rear portion of the carriage, the column-stop being adjustable along a rack which is accessibly mounted upon the upper rear portion of the carriage.

4. In a typewriting machine, the combination with a spring-propelled carriage and a letter-spacing mechanism, of manually-operable instrumentalities effective for releasing said carriage from control of said letter-spacing mechanism, and devices for applying a braking force effective for restraining said carriage when released from said letter-spacing mechanism, said braking devices including a yieldable brake-strap and two brake-jaws to grip the strap, each jaw having a friction surface, a key-operated arm upon which one of said jaws is provided, and a carriage-arresting stop upon said arm.

5. The combination with a letter-feeding typewriter-carriage and a tabulating mechanism, of a carriage-retarding device therefor, a counter-stop connected to be moved to effective position when the carriage is released, a shouldered detachable column-stop co-operating with said counter-stop to arrest the carriage, a rack provided on said carriage for adjustably supporting said column-stop, and a bail hinged upon the carriage and including a locking bar extending along said rack to engage the shoulder on the column-stop, said rack, column-stop and locking bar being mounted on the upper rear portion of the car-

riage in accessible position, and said carriage releasing and retarding devices including a rock-shaft from which extends upwardly an arm carrying said counter-stop, said arm having a friction jaw, and a strap pressed between said friction jaw and a stationary friction jaw upon the machine.
